SPHERICAL CLEANER—GENERAL
ARRANGEMENT

George P. Daiger, Canton, Dale C. Gerber, North Canton, and Werner G. Seck, Canton, Ohio, assignors to The Hoover Company, North Canton, Ohio, a corporation of Ohio

Application March 25, 1954, Serial No. 418,556

11 Claims. (Cl. 183—37)

It is a general object of our invention to provide a cleaner characterized by maximum efficient utilization of the space within the cleaner casing to the end that the casing is reduced to the minimum practical size consistent with the size of the objects which it must house, and the presentation of an acceptably pleasing external appearance, and which may be constructed at minimum cost while retaining maximum efficiency of operation, and ease of construction and servicing.

It is a particular object of our invention to provide a suction cleaner having a power plant and filter structure housed within a generally spherical casing whereby a maximum volume of space is provided for these elements with a minimum external surface.

It is a further object of our invention to provide a suction cleaner housed within a spherical casing, divided along a substantially diametrical plane into hemispheres so arranged that the power plant is substantially completely housed within one of the hemispheres and the filter is supported from the hemisphere housing the motor fan unit but positioned entirely within the other hemisphere upon a skeletal frame whereby removal or pivoting of the upper hemisphere completely exposes the filter for maximum ease of replacement or inspection of the filter.

It is another object of our invention to provide a suction cleaner of the foregoing type wherein the filter is provided with an air inlet held in a skeletal frame in proper position to register with the air inlet conduit of the cleaner without attention on the part of the operator when the cleaner casing is closed.

It is a further object of our invention to provide a suction cleaner of the character generally above set forth constructed and arranged to provide maximum ease of access to the various parts thereof to facilitate installation, construction, servicing and maintenance.

It is a further object of our invention to provide a suction cleaner wherein the filter and power plant are encased within a generally spherical casing which is pivotally supported upon a base frame connected to the spherical casing to provide a substantially continuous circumferential slot between the upper portion of the base frame and the spherical casing and wherein air exhausted from the cleaner discharges into the interior of the base frame and is then diffused through the circumferential slot.

It is another important feature of our invention that the filter mounting and support structure not only provides completely free access to all portions of the filter but is resilient to insure proper engagement between the filter and air inlet conduit independently of accumulated tolerances in a particular cleaner and to eliminate close tolerances in the air inlet and filter structures without detracting from the efficiency of the cleaner.

It is a further important object of our invention to provide a suction cleaner wherein the motor fan unit is positioned in the lowermost portion of a spherical casing with the heavier portion of the motor on the underside of the motor fan unit very close to the level of the supporting surface to provide maximum stability in the structure and

2

maximum ease of movement thereof across a supporting surface.

It is still another object of our invention to provide a suction cleaner wherein the filter is housed within a spherical casing in such fashion as to utilize effectively a large area filter without cramping or blocking any part of the filter structure and without providing significant waste space in the filter housing part of the cleaner.

Other objects and advantages of the invention will become apparent as the description proceeds when taken in connection with the accompanying drawing wherein:

Figure 1 is a sectional elevational view of a suction cleaning apparatus embodying our invention,

Figure 2 is a partial elevational view, partly in section, taken at right angles to the section of Figure 1 to illustrate certain hinge and latch details,

Figure 3 is a perspective view drawn to a smaller scale illustrating the complete cleaner opened to expose the filter, and

Figure 4 is a perspective view of the complete cleaner, also drawn to a smaller scale, illustrating the manner in which the cleaner is converted for blowing operation.

Referring now to the drawing in detail, and first to Figure 1 thereof, our invention is illustrated as comprising a casing referred to generally by the reference character 1 which is spherical in shape and is composed, in the illustrated embodiment, of hemispherical sections 2 and 3, respectively. The upper hemisphere 2 is pivotally joined to the lower hemisphere 3 by means of a hinge 4. The two hemispheres are secured in assembled relation by a latch mechanism which comprises a toggle latch 5 attached to the upper hemisphere 2 and having a catch portion 6 which is engageable under a keeper tongue 7 projecting outwardly of the lower hemisphere 3 and secured thereto as by welding or the like. In the illustrated embodiment of the invention, the hemispheres 2 and 3 join on a horizontal diametrical plane indicated generally by the reference character 8. The lower hemisphere 3 has a circumferential guard or bumper 9 secured to the outside surface thereof which projects slightly above its upper edge so as to overlap the lower edge of the hemisphere 1 when the two hemispheres are in the assembled relation illustrated. A second circumferential, ornamental guard or bumper 10 is mounted on the lower portion of the upper hemisphere 2 just above the lower edge thereof. The bumper or guard 10 is continuous except for an interruption to accommodate the latch mechanism 5 as shown in Figure 4. The overlapping relation of the bumper 9 to the meeting edges of the hemispheres 2 and 3 effectively seals the joint therebetween against air leakage.

An annular stiffening rib 12, L-shaped in cross section, is secured as by welding or the like to the interior of the upper hemisphere 2 and projects slightly below the edge thereof to hold the lower edge of the hemisphere 2 in true circular relationship and to guide it into proper engagement with the upper edge of hemisphere 3.

The interior of the spherical casing 1 is divided into substantially equal upper and lower chambers 13 and 14 by means of a transverse partition or bulkhead 15. The outer edge of the bulkhead 15 rests upon the horizontal portion of an annular L-shaped stiffening rib 16 and secured to the inner surface of the lower hemisphere 3 just below the free edge thereof. The member 16 supports the bulkhead 15 and maintains the free edge of the hemisphere 3 in true circular condition to insure that it will also mate properly with the edge of the hemisphere 2.

A power plant unit of known type is mounted within the chamber 14 and consists essentially of a casing 17 within which is housed a multistage fan or air pump of a type commonly used in suction cleaners. The casing 17 is provided with a central, upwardly-facing inlet opening 18 by which air is led to the fans contained in the

casing 17. The casing 17 is secured as by means of studs 19 to the upper end of a motor frame 20 which houses and supports an electrical motor 21 which drives air fans within the housing 17 in a known manner.

The power plant assembly consisting of the motor and fan structure is maintained in position within the chamber 14 between the bulkhead 15 and the bottom portion of the hemisphere 3. The lower portion of the hemisphere 3 is deformed to define a cup-shaped recess or depression 22 within which is mounted a resilient gasket 23, preferably formed of rubber or similar material, provided in its central portion with a closed bottom conical opening 24. The lower end of motor housing 20 is provided with a downwardly-projecting truncated conical section 25 which is wedged into the resilient gasket 23 whereby to form a resilient and sound-deadening bottom support for the motor and fan structure.

The upper end of the power plant structure engages against an annular gasket 26 of rubber or similar material which is received within an upwardly-projecting, cup-shaped recess 27 formed in the central part of the bulkhead 15. The recess 27 is provided with a central opening 28 to permit free flow of air through the bulkhead 15 into the air inlet opening 18 of the power plant without, however, permitting air to flow by any other means between the spaces 13 and 14.

An annular barrier member 30 L-shaped in cross section rests upon and is suitably secured to the upper face of bulkhead 15. The barrier 30 serves to position and support a dish-shaped felted paper or fiber secondary filter 31 which rests upon and is stiffened by a complementally shaped screen 32.

Referring now particularly to Figures 1 and 3, the principal filter and its supporting mechanism will be described. The bulkhead 15 supports a spaced pair of resilient U-shaped strap members 33 and 34 defining the principal elements of a skeletal frame for supporting a principal filter. For purposes of convenience in description, the frame member 33 is referred to as the front frame and the member 34 as the rear frame. The members 33 and 34 are secured to the bulkhead 15 and to the annular spacing member 16 by means of studs 35 which extend through suitable openings in the bulkhead 15 and thread into the member 16. The strap members 33 and 34 are positioned so as to substantially conform to the contour of the hemisphere 2 with their leg portions adjacent but inwardly spaced from the periphery thereof. The member 30 lies within the frame members 33 and 34 as shown in Figure 3.

The top or bight portions of the members 33 and 34 are horizontal and are connected by spaced channel members 37 which underlie the bight portions of the strap members and are secured thereto as by welding or the like.

The channel members 37 provide supporting guides for a filter mounting means to be described. The ends of the channel members 37 connected to the strap member 34 are closed to form stops and the ends of channel members 37 connected to the strap member 33 are open as shown in Figure 3 to permit insertion of a filter mounting and support member to be described hereinafter.

In the illustrated embodiment my invention is provided with a primary filter 40 which is preferably constructed in the form of a tubular bag closed at its opposite ends as indicated at 41 and connected by suitable pleats indicated at 42. This type of bag construction is characterized by substantially flat upper and lower sides when positioned as illustrated in Figure 3. The upper flat side of the filter 40 is provided with a lanced inlet opening as indicated at 43. A felt sealing and reinforcing ring 44 is cemented to the top surface of the filter 40 around the opening 43 and is in turn cemented to a flat rectangular cardboard mounting plate 45 sized to slide into the channel-shaped members 37 as is illustrated in Figures 1 and 3. When the plate 45 is slid into the channels 37 to the maximum extent permitted by the closed ends thereof, the filter as-

sumes the position illustrated in Figure 3 from which it is apparent that the same is entirely exposed for inspection when the top hemisphere member 1 is swung to the open position. It is also apparent that the filter is readily removed from the skeletal supporting frame by simply sliding the same forwardly as viewed in Figure 3 and may be replaced by sliding the mounting plate 45 of the new filter into the channels 37 rearwardly as viewed in Figure 3. The tubular pleated form of filter assumes a roughly hemispherical form when inflated thus providing large effective filtering area and substantially filling the hemisphere 2.

The top hemisphere 2 is provided in its top central portion with a tubular inlet connection conduit 46 sized to fit within the lanced opening 43 of the filter and to form an air seal therewith by engaging the inner edge of the felt ring 44 and the side walls of the lanced openings 43. It is apparent from Figure 1 that the plate 45 is provided with an opening 47 of considerably larger diameter than the conduit 46 to permit the same freely to pass through the plates 45 without engaging the same. The plate 45 is a mounting and supporting device and is not intended to form a part of the air seal between the inlet conduit and the filter proper.

The conduit 46 is provided with an enlarged diameter section 48 terminating in an outwardly-projecting flange 49 which is secured to the inside wall of the hemisphere 2 by welding or similar means. The enlarged diameter portion 48 of the inlet conduit receives an annular anchoring ring 50 which is in the shape of an inverted L in cross section. The ring 50 cooperates with the member 46 to form an annular channel 51 just within the confines of the hemisphere 1. The ring 50 is secured to the enlarged diameter portion 48 of the inlet conduit by welding or similar means.

The inlet conduit structure just described is adapted to receive an elbow-shaped hose connecting swivel conduit 52. The tubular elbow 52 is provided with a downwardly-projecting leg portion 53 which is pivotally received within the conduit 46 to form an air connection therewith while permitting the elbow 52 to swivel freely on a vertical axis within the conduit 46. The elbow 52 is provided in one side thereof with a spring-mounted latch member 55 having on its lower end a projecting pin or tongue 56 which extends into the annular channel 51 to prevent accidental separation of the elbow 52 while allowing the same to turn freely about a vertical axis. Depressing the spring 55 inwardly from the plane of view of Figure 1 withdraws the pin 56 from the channel 51 to permit disassembly of the elbow from the hemisphere 2 if desired.

The other leg of the elbow 52 is provided with a tubular section 58 having on its outer end an enlarged diameter channel forming section 59. The member 58 is adapted to receive a tubular mounting portion 60 of a flexible hose 61 adapted to be connected to a suction tool 63. The hose 61 is provided with a spring latch mechanism of known type indicated generally at 64 and provided with a projecting pin or tongue part 65 adapted to be received within the channel 59 to prevent longitudinal withdrawal of the hose from the tubular connector 58. Depression of the portion 64 of the connecting structure withdraws the member 65 from the channel 59 to allow ready disassembly of the hose from the elbow connector 52.

As shown in Figure 3, the upper hemisphere 2 is in its removed or open position with respect to the lower hemisphere 3. The extent of pivotal movement of the member 2 is limited by a light-weight chain 66 connected to a suitable hook member 67 mounted on the interior wall of the hemisphere 2 and to hook 68 carried by the frame member 34 at opposite sides thereof. The length of the chain 66 is such that the hemisphere 2 can tilt backwardly slightly beyond the vertical to remain in the position illustrated in Figure 3.

When a filter is properly positioned in the channel members 37, the hemisphere 2 may be swung in a forward or clockwise direction as viewed in Figure 3 to the closed position of Figure 1 in the course of which the tubular connector 46 passes into the inlet opening of the filter and forms a seal therewith as described heretofore. Similarly, when the top hemisphere 2 is swung to the filter exposing position of Figure 3, it automatically detaches the connector 46 from the filter so that the filter is then freely removable and replaceable.

The cleaner supporting structure comprises a substantially plane surfaced supporting plate or skid 70 which is curved upwardly and its peripheral portion is indicated at 71. The disc-like skid 70 supports an annular member of substantially the same maximum diameter which comprises an outer conical section 72 which is turned down at its end to join the upturned edge 71 of the member 70 to which it is secured as by welding. The conical section 72 joins a reversely inclined conical section 73 which terminates in a vertical ring section 74 joining an annular flange 75 resting on the upper surface of the member 70. The flange 75 is also secured to the member 70 as by welding or the like. The inclined section 73 of the supporting ring carries a plurality, two are illustrated, of spaced-apart resilient pads 76 which are adapted to engage the surface of the spherical member 3 and to cooperate with a hinge means to be described to maintain the member 3 spaced from the flange 73 so as to provide a substantially continuous annular discharge port between the conical ring 73 and the wall of the spherical member 3.

As shown most clearly in Figure 2, the portions 73, 74 and 75 of the supporting ring structure is interrupted to provide space for a hinge 78 having one leaf thereof riveted or otherwise suitably secured to a raised portion 79 of the base skid 70 and the other portion thereof bolted as indicated at 80 in an indented angular section 81 of the spherical member 3. The hinge 78 provides the means by which the supporting structure is secured to the spherical casing 1 and a means whereby the spherical casing 1 can be pivoted away from the supporting structure for a purpose to be described hereinafter.

Oppositely to the hinge 78, the supporting ring 73 is provided with an opening 82 through which projects the hook portion of a latch spring member 83 secured as by the rivet 84 to the annular member 74. The hook portion of the spring latch 83 is adapted to engage a catch 85 which is secured to the underside of the hemispherical member 3 in position to be engaged by the latch spring 83 when the spherical member is resting on the resilient pads 76. A release arm 86 is secured to the spring member 83 and projects through an opening 87 in the conical ring member 72 so as to be accessible from the exterior thereof for disengaging the latch 83 from the keeper 85.

As shown most clearly in Figure 1, the hemispherical member 3 is provided with an exhaust conduit 88 positioned to discharge exhaust air within the confines of the supporting structure when the parts are in the assembled relation illustrated in Figures 1 and 2. The exhaust conduit 88 has an enlarged diameter section 89 terminating in an outwardly-projecting flange 90 which is secured to the interior of the hemispherical member 3. An annular L-section ring member 91 is secured within the enlarged portion 89 of the exhaust conduit to define an annular channel 92 therewith which is adapted to receive a latch member on a suction cleaner hose such as the member 65 to convert the apparatus for blowing operation. In the use of the apparatus for normal cleaning, the air discharged by the fans within the housing 17 discharges through the conduit 88 into the interior space between the bottom portion of the hemispherical member 3 and the base supporting skid 70 and escapes between the outer surface of the hemispherical member 3 and the member 73 substantially around the entire periphery of the hemisphere 3. The circumferential slot between 75 connector.

members 3 and 73 forms an exhaust diffuser for the cleaner which directs the air upwardly away from the supporting surface in a low velocity annular stream.

When it is desired to convert the apparatus into blowing operation, the latch 83 is released from the keeper 85 after which the spherical casing 1 can be pivoted on the hinge 78 away from the supporting structure as illustrated in Figure 4. When this is done, the exhaust conduit 88 is exposed and a hose such as the hose 61 may be readily attached thereto as illustrated in Figure 4. The spherical cleaner casing pivots on the hinge 78 until the outer periphery thereof rests on the supporting surface externally of the outer periphery of the normal supporting skid 70 and its associated structures when converted to blowing operation. The leaf of the hinge 78 directly connected to the hemisphere 3 is provided with a deep U-shaped section 93 so as to clear the joint between the supporting ring sections 72 and 73 whereby the major portion of the weight of the spherical casing 1 is supported by contact of that casing with a supporting surface when converted to blowing operation.

The upper hemispherical section 2 is provided with spaced pairs of U-shaped mounting brackets 100 positioned on opposite sides of the inlet connecting conduit 46 and in spaced relation thereto. The brackets 100 have leg portions projecting through the wall of the hemisphere 2 from the interior thereof to form spaced-apart supports for pivoting pins 101 upon which is pivotally mounted a bail type carrying handle 102. When the cleaner is in use, the handle 102 lies flat against the same so as to be clear of the elbow 52 allowing 360° swiveling movement of the elbow member 52 under these conditions. When the hose 61 is disconnected from the elbow 52 the bail type handle 102 can be raised for easy transportation of the cleaner structure.

A conventional type of snap acting switch 104 is mounted on the exterior wall of the hemispherical section 3 directly below the latch mechanism 5 and above the latch release lever 86. Thus, all the control and actuating mechanisms are positioned together on one side of the spherical casing for ready access. The switch 104 controls the electrical motor 21 to which it is connected on a conventional manner by wires, not shown. Additionally, the cleaner will be provided with a conventional service cord, also not shown, which will pass through the wall of hemispherical section 3 in a conventional type of protective mounting.

The above described cleaner is characterized by the provision of a number of highly desirable characteristics. 50 The housing spherical structure provides for a maximum internal volume with minimum external surface as well as providing a pleasing and regular appearance. The arrangement of motor and fan in the bottom half of the spherical casing with the motor at the lower part of the power plant unit places the heaviest portions of the internal cleaner structure at the lowest possible level to provide maximum stability and easy sliding on a supporting surface in response to a force applied to the suction cleaning hose 61 by the operator. Since the supporting structure also provides the exhaust air diffusing means, the exhaust structure in the cleaner casing proper is a purely conventional standard type of hose connecting device wherefore the hose may be connected directly thereto for blowing operations without requiring valve manipulation or similar steps to handle conversion and diffusion.

It is a particularly important feature of our invention that the filter is supported on a skeletal frame carried by the lower hemispherical section of the cleaner casing but is positioned entirely within the upper hemispherical casing section whereby pivoting the upper section away from the lower section exposes the filter completely and disconnects the air inlet connection to facilitate inspection and replacement without requiring the operator to stuff the filter into cramped quarters or to establish an air inlet

An important feature of the invention also resides in the arrangement of the secondary filter which, as shown in Figure 1, arches upwardly over the air inlet portion of the fan casing 17 and in spaced relation thereto. This arrangement provides a strong support for the bottom portion of the filter 40 where heavy dirt and metallic particles are likely to collect and also prevents the bottom portion of the filter from sealing against the inlet opening through the bulkhead 15 so as to maintain all portions of the filter 40 operative at all times to filter air which can pass through the portions of the secondary filter 31 spaced from the filter 40 and thus find their way freely into the fan casing 17.

While we have illustrated and described the invention in considerable detail, it is to be understood that various changes may be made in the arrangement, proportion and construction of parts without departing from the spirit of the invention or the scope of the appended claims.

We claim:

1. Suction cleaning apparatus comprising a spherical cleaner casing having air inlet and exhaust conduits, a tubular filter in the casing mounted to receive air from the air inlet, a suction producing unit mounted in the casing and arranged to draw air through the air inlet and filter and to discharge air through the exhaust conduit, a support structure attached to the casing including an upstanding annular wall having a lower surface engaging section and an upper section positioned in spaced relation to the casing to define an annular exhaust diffusing port therewith and the said exhaust conduit being positioned to discharge into the support structure and within the annular wall, said support structure being pivotally attached to the casing whereby the casing may swing away from the support structure to expose the exhaust conduit for connection of a flexible hose thereto.

2. Suction cleaning apparatus comprising a casing composed of first and second sections separably joined together, a filter having an air inlet housed in said first section, a suction producing unit housed in said second section, an air inlet connection on the first casing section, and a resilient filter support on the second section supporting the filter in the first section with the filter air inlet engaging the air inlet connection whereby the filter is exposed and disengaged from the air inlet connection when the casing sections are separated, said first casing section being substantially hemispherical and said filter comprising a tubular body substantially filling the first section when inflated, said filter being provided with a mounting panel surrounding the filter air inlet and said filter support comprising a resilient frame structure carrying a mounting means releasably engaging the panel and supporting the filter with the filter air inlet held in operative relation to the air inlet connection.

3. A suction cleaner comprising, a hollow sectional casing, a support for said casing, a bulkhead dividing said casing into substantially equal volumes, said casing being separably connected at said bulkhead to form upper and lower parts with said bulkhead mounted on said lower part and having a central opening between said parts, suction creating means mounted within said lower part, an air inlet connection formed in said upper part remote from said bulkhead, a filter having an air inlet opening within said upper part and substantially occupying its entire vol-

ume when in its inflated condition, means for supporting said filter within said upper part with said air inlet in alignment with said air inlet connection, said supporting means being attached to said bulkhead adjacent the edge thereof and comprising a skeletal frame extending upwardly along the inner wall of said upper part and an inwardly extending portion in alignment with said air inlet connection and means for detachably connecting said filter to said inwardly extending portion with said inlet opening in alignment with said inlet connection whereby said filter is fully exposed for removal and replacement when said upper part is separated from said lower part.

4. A suction cleaner according to claim 3 in which said suction creating means comprises a motor-fan-unit having a suction inlet communicating with the central opening in said bulkhead and with the motor extending downwardly to adjacent the bottom of said lower part whereby the center of gravity of the cleaner is positioned below said bulkhead.

5. A suction cleaner according to claim 3 in which said detachable connecting means includes a platelike member secured to said filter about said inlet opening and means on the inwardly extending portion of said filter supporting means for slidably and detachably securing the edges of said platelike member whereby said filter may be easily detached and replaced when said upper part is separated from said lower part.

6. A suction cleaner according to claim 3 including a hinge connection between said upper and lower parts at one side thereof so that said upper part may pivot upwardly about said hinge and not interfere with said filter or with said filter supporting means.

7. A suction cleaner according to claim 6 in which said casing is of spherical formation and its upper and lower parts are in the form of hemispheres mating at their diametrical faces.

8. A suction cleaner according to claim 6 including means attached to said filter supporting means for limiting the pivotal movement of said upper part to a position slightly over center relative to said hinge so that said upper part will remain open when moved to that position.

9. A suction cleaner according to claim 3 in which said upper and lower parts are substantially hemispherical in shape and mate with each other about their diametrical faces.

10. A suction cleaner according to claim 3 in which said filter comprises a paper filter bag closed at both ends, said bag having at least one flat side with said inlet opening formed therein and having pleated sides adjacent said flat side.

11. A suction cleaner according to claim 3 in which said inlet connection seals with said inlet opening when said upper part is connected to said lower part.
